United States Patent Office

Des. 212,650

Patented Nov. 5, 1968

212,650

TELEVISION CAMERA

Donald E. Leman, Glen Ellyn, Ill., assignor to Ampex Corporation, Redwood City, Calif., a corporation of California

Filed June 7, 1967, Ser. No. 7,395

Term of patent 14 years

(Cl. D61—1)

FIG. 1

FIG. 2

FIG. 3FIG. 4FIG. 5

FIGURE 1 is a side and front perspective view of a television camera, showing my new design;

FIGURE 2 is an opposite side, top and rear perspective view;

FIGURE 3 is a top plan view;

FIGURE 4 is a front elevational view; and

FIGURE 5 is a rear elevational view thereof.

The dominant features of my new design are shown in solid lines in the drawing. Portions of the drawing figures are diagonally lined to indicate transparency.

I claim:

The ornamental design for a television camera, substantially as shown and described.
